UNITED STATES PATENT OFFICE.

IRA L. FRENCH, OF CHICAGO, ILLINOIS, ASSIGNOR TO THE MANTLE LAMP COMPANY OF AMERICA, OF CHICAGO, ILLINOIS, A CORPORATION OF ILLINOIS.

DESIGN FOR A LAMP-SHADE.

51,923.

Specification for Design.

Patented Apr. 2, 1918.

Application filed January 2, 1918. Serial No. 210,093. Term of patent 14 years.

To all whom it may concern:

Be it known that I, IRA L. FRENCH, a citizen of the United States, residing at Chicago, in the county of Cook and State of Illinois, have invented a new, original, and ornamental Design for a Lamp-Shade, of which the following is a specification, reference being had to the accompanying drawing, forming a part thereof.

Figure 1 is a top plan view of the lamp shade, and
Fig. 2 is a side elevation of the same.
I claim:
The ornamental design for a lamp shade,
as shown.

IRA L. FRENCH.
